tion of Delaware

Application September 15, 1943, Serial No. 502,440

2 Claims. (Cl. 196—40)

1

This invention relates to treating hydrocarbons, and more particularly, relates to acid-treating of catalytic naphthas to improve the anti-knock quality of aviation gasoline or blending stock.

It is known that certain olefins are undesirable constituents in aviation gasolines and different methods have been described for removing undesirable olefins from such fractions. Some of these methods are referred to hereinafter. It has been reported that sulfuric acid treatment of low sulfur catalytic naphthas in the aviation gasoline boiling range results in no significant improvement in either AFD-1C and AFD-3C anti-knock quality (presently to be described), and in some cases results in decrease in AFD-3C quality. These results apply particularly to the sulfuric acid treatment of a total aviation naphtha in the C₅-350° F. range.

The AFD-1C method of evaluating aviation gasoline anti-knock quality is carried out in accordance with Army-Navy specification AN-VV-F-746. This rating is designed to be a measure of the anti-knock quality of the fuel under lean-mixture conditions such as would exist under cruising conditions in aircraft. The rating is expressed in terms of the volume per cent of iso-octane that must be blended with normal heptane to give a blend which will just equal the anti-knock quality of the test sample in the AFD-1C engine.

The AFD-3C rating is designed to indicate the anti-knock quality of the gasoline under rich mixture conditions such as are encountered in aircraft operations under take-off or combat operations. The rating is generally expressed in terms of the volume of lead tetraethyl (milliliters per U. S. gallon) that must be added to "S" Reference fuel (commercial iso-octane) to match the anti-knock quality of the test samples in the AFD-3C test engine. The rating is sometimes expressed in terms of the indicated mean effective pressure (IMEP) developed in the AFD-3C test engine. The AFD-3C rich mixture testing is made according to Army-Navy specifications AN-VV-F-748, and the rating obtained is directly proportioned to the maximum knock-free power of an engine using this fuel. Therefore, fuels of

2

high AFD-3C quality are more desirable since they will give more knock-free power in the aircraft engine.

I have found that by separating catalytically cracked naphtha of relatively high olefin content into two or more fractions and separately treating these fractions with concentrated sulfuric acid rather than acid-treating the total naphtha cut, substantial increases in AFD-1C, and more particularly in AFD-3C anti-knock quality are obtained. The total catalytically cracked naphtha fraction contains olefins, aromatics, naphthenes, and paraffins, and if the total naphtha fraction containing a large percentage of olefins is treated with sulfuric acid, some aromatics are lost by the alkylation of aromatics with olefins. If the separate fractions are acid-treated, there is less loss due to alkylation because the aromatics are concentrated in the higher boiling fraction or fractions and the ratio of aromatics to olefins is then unfavorable to the alkylation reaction. My improved results are apparently due to the more selective removal of olefins, the removal of which results in the concentration of aromatics and naphthenes.

In addition to the possibility of acid-treating naphthas in conventional equipment, my process can readily be installed in refineries where sulfuric acid alkylation is practiced with a small expenditure for contacting and rerunning.

In the drawing;

Fig. 1 represents one form of apparatus which may be used to carry out my process; and

Fig. 2 represents another form of apparatus wherein my process may be used in a refinery which practices sulfuric acid alkylation of lower boiling hydrocarbons.

In the catalytic cracking of relatively heavy hydrocarbons, such as gas oils, to produce lower boiling hydrocarbons, the gasoline produced contains aromatics, olefins, naphthenes, and paraffins. The aromatics, naphthenes and branched chain paraffins are desirable constituents for aviation gasoline but olefins are generally undesirable.

One method for removing olefins is acid-treating, which has long been practiced in petroleum

refineries. Conventional acid-treating is, however, not desirable for treating catalytically cracked fractions. For example, in the production of aviation gasoline, it has been reported that there is a loss in AFD-3C rating of the aviation gasoline if it is acid-treated with concentrated sulfuric acid. I have found, however, that if the aviation gasoline or naphtha fraction is divided into two or more fractions, and each fraction treated separately with sulfuric acid of concentrations and acid consumptions optimum for each fraction, that an actual increase in the AFD-3C rating is obtained.

There are other ways of removing olefins or separating aromatics or naphthenes from the cracked gasoline, and my process compares favorably with them. Other processes are catalytic after treating of the catalytically cracked gasoline, hydrogenation of the catalytically cracked naphtha and solvent extraction of the catalytically cracked naphtha.

Referring now to Fig. 1 of the drawings, the reference character 10 designates a line for conveying catalytically cracked naphtha to a fractionating tower 12 for separating the naphtha into desired fractions. For example, a gas oil is cracked at a temperature of about 925-1000° F., preferably 975° F. in the presence of a catalyst, such as synthetic gels, acid-treated bentonites, etc., preferably silica-alumina gel catalyst. The cracked naphtha is separated from the cracked products. C₄ and lighter are taken overhead through line 14 and may be sent to storage or utilized in any desired manner. A C₅ to 225° F. fraction is withdrawn as a side stream through line 16. A heavier fraction having a boiling range of about 225 to 350° F. is withdrawn as a lower side stream through line 18. Bottoms are withdrawn through line 22. These bottoms contain higher boiling constituents which may be used in ordinary motor gasoline.

The C₅ to 225° F. fraction contains most of the olefins and the 225 to 350° F. contains most of the aromatics as will be hereinafter described when the composition of these fractions is given. However, both fractions contain olefins and it is preferred to acid-treat both of the fractions.

The C₅ to 225° F. fraction is introduced into an acid-treating tank 24 provided with a stirrer 26 or other suitable means of providing intimate contact between acid and naphtha. Concentrated sulfuric acid having a concentration of about 85 to 98% is introduced into the tank 24 through line 28 and acid sludge is withdrawn through line 32. The amount of acid used may vary between about 5 to 60 pounds of sulfuric acid per barrel of oil treated, depending on the olefin content of the naphtha, the improvement desired, and the strength of acid that is to be used in treating. Preferably, about 20 to 30 pounds of sulfuric acid (98%) per barrel of oil is used. The temperature may vary between about 30 to 120° F.

The time of contact of the acid and the oil fraction is from 2 to 120 minutes, longer times being used with weaker acid. The acid treatment removes a large part of the olefins and the treated C₅ to 225° F. fraction is withdrawn through line 34 and passed through a wash tank 36 where the fraction is washed with alkaline water to remove entrained acid. The washed fraction is then passed through line 38 to a fractionating tower 42 for rerunning the treated fraction.

The desired volatile fraction passes overhead from the fractionating tower 42 through line 44

and condenser 46 to a liquid gas separator 52 wherein uncondensed gases and vapors are separated from liquid. The gases or vapors pass overhead through line 54 and the liquid is withdrawn from the bottom of the separator 52 through line 56. At least a portion of the liquid withdrawn through line 56 is passed through line 58 by pump 62 and returned to the fractionating tower 42 as reflux liquid. The rest of the liquid from line 56 forms the desired lighter treated fraction and will be referred to hereinafter.

Bottoms from the fractionator 42 are withdrawn through line 64. These bottoms contain higher boiling constituents in the gasoline boiling range and may be used as blending agents for ordinary motor gasoline.

The 225 to 350° F. fraction is given a similar treatment though the optimum treating conditions may differ from those for the light fraction.

The 225-350° F. fraction is passed to an acid-treating tank 66 provided with a stirrer 68 or other means of providing required mixing. Concentrated sulfuric acid having a concentration of about 85 to 98% is introduced into the tank 66 through line 72 and after sludge is withdrawn through line 74. The amount of sulfuric acid used is about 5 to 60 pounds per barrel of oil fraction treated, depending on acid strength, the olefin content of the fraction, etc. The time of mixing and reaction in the acid tank 66 is from about 2 to 120 minutes, longer times being used with weaker acid. The temperature during treating is about 30° F. to 120° F.

The acid-treated 225 to 350° F. fraction is then passed through line 76 to another wash tank 78 where the fraction is washed with alkaline water to remove entrained acid. The washed 225-350° F. fraction is then passed through line 82 to a second fractionating tower 84 for recovering the desired treated fraction. Instead of using two fractionators 42 and 84 for the separate fractions, the fractions may be combined and fractionated in one fractionator.

As above pointed out, the heavier fraction also contains olefins and the acid treatment removes a large part of the olefins. In the fractionating tower 84 the treated heavier fraction is heated and fractionated to separate a desired 225 to 350° F. fraction. Higher boiling constituents are drawn off as bottoms through line 85 and may be used as blending agents for ordinary motor gasoline.

The vapors pass overhead from the fractionating tower 84 through line 86 and condenser 88 to a liquid gas separator 92 for separating liquids from gases and vapors. The gases and vapors pass overhead through line 94. The liquid is withdrawn from the bottom of the separator 92 through line 96 and at least a portion thereof is passed through line 98 by pump 102 and returned to the top of the fractionating tower 84 as reflux liquid. The rest of the liquid is passed through line 104 and combined with the treated lighter fraction passing through line 106 which forms a continuation of line 56. The combined naphtha fractions are withdrawn from the system through line 108. The combined treated naphtha fraction has a higher AFD-1C and a higher AFD-3C rating than the total naphtha fraction would have if acid-treated as a single fraction.

The following data represent one example to show the improved results which are obtained with my process when applied to aviation gasoline fractions containing substantial proportions of olefins and aromatics:

Table 1.—Acid treated fractions compared with acid treated total naphtha

	Bromine No. Decrease	Treating Loss Vol. Per cent on Feed	Time of Treating	Quality Increase	
				AFD-1C ¹	AFD-3C ¹
H_2SO_4 —98% 10#/Bbl. of Oil Treated: C ₆ —225° F. 225—350° F.	23 7	15 6.0	Minutes 3 3	3.3 3.5	8.1 12.7

¹ Ratings based on fuel containing 4 ml. TEL/gal.

The above table discloses data to show that there is a quality increase in the aviation naphtha when the naphtha is divided into two fractions and each fraction separately acid-treated. These data show that the total recombined naphtha after separate acid-treating of the fractions has a much greater AFD-1C increase than the total naphtha C₆ to 350 when it is acid-treated as a single fraction. These data further show that there is an increase in AFD-3C rating when the fractions are separately treated whereas when the total naphtha fraction is acid-treated as a single fraction there is a decrease in AFD-3C rating.

Table 2.—Composition of fraction-vol. percent

Fraction	Aromatics	Naphthenes	Olefins	Paraffins	Bromine No.
C ₆ —225° F.	4	21	44	31	80-95
225—350° F.	68	13	19	0	15-26
Total Fraction	36	17	31.5	15.5	55-75

composition of such a naphtha is given in Table 2. A catalytically cracked gasoline of this type having a boiling range of about 100—335° F. has and AFD-3C rating at about 170—180 IMEP.

Only one example of catalytically cracked naphtha has been given and it is to be understood that the amounts of the different constituents may vary with different feed stocks and different cracking conditions, such as temperature, time of cracking and amount and kind of catalyst used, but it is generally true that the amount of olefins in the lighter fraction is greater than in the heavier fraction and the amount of aromatics in the lower boiling fraction is much less than the amount of aromatics in the higher boiling fraction.

The amount of improvement to be gained in treating the naphtha fractions varies with the amount of acid employed as well as the strength of the acid. The following Table 3 discloses the effect of acid quantity on the light and heavy naphtha fractions when treating with 98% strength used:

Table 3

	# H_2SO_4 —98% per Bbl. of Oil	Vol. Per Cent Loss on Treating	Quality Improvement			Time of Treating

	30	17	19	6.0	43.3	3

¹ Rating with 4 cc. tetraethyl lead added to samples.

Table 2 discloses a typical composition of catalytically cracked gasoline. Paraffinic gas oil having an A. P. I. gravity of 31.5° and a mid boiling point of 650° F. was cracked at a temperature of about 975° F. in the presence of synthetic silica alumina gel at about 65% conversion, which means that about 65% of the original gas oil is converted to gas, coke and gasoline, and that there is 35% cycle oil left. Cracked naphtha is separated from the cracked products and the

From the above Table 3 it will be seen that with the more drastic sulfuric acid treats greater improvement in the AFD-1C and AFD-3C ratings is obtained but at the same time greater loss of feed results. Table 3 also illustrates that the quality improvements to be gained at fixed treating conditions, vary, depending on the boiling range and/or composition of the naphtha; thus, to obtain a given overall quality improvement my process of treating selected fractions is also a

more efficient scheme from a standpoint of acid consumption and treat severity inasmuch as each fraction can be treated separately more effectively than when combined.

Table 4 shows that to obtain a given quality improvement, the losses from acid-treating the heavy fractions are much lower than the light fraction; also, acid-treating the light and heavy fractions separately and recombining them give an increase in quality with a lower loss than when acid-treating the total naphtha.

Table 4.—Effect of given acid treat on various fractions

Catalytically Cracked Naphtha Fraction	Light	Heavy	Total	Treated Light and Heavy Recombined

Loss/AFD-3C IMEP Improvement	1.8	0.4	(2)	1.0

¹ 98% H₂SO₄. ² Negative.

Table 5 illustrates the acid treats that would be required for two naphthas of different unsaturation content. It will be observed that to obtain a given quality improvement less acid is required by treating separately and recombining. Optimum trends for each fraction, however, depend on their unsaturation content.

¹ 98% H₂SO₄.

Notes:

1. High unsaturated naphtha from 975° F., 65% conversion cracking of heavy Tinsley gas oil.
2. Low unsaturated naphtha from 975° F., 80% conversion cracking of heavy Tinsley gas oil, using higher catalyst to oil ratio than for the 65% conversion.

A typical application of my process in a refinery producing aviation gasoline is illustrated in Fig. 2. Referring now to Fig. 2 of the drawings, the line 120 designates a line for conducting a heavy oil stock, such as gas oil, to a cracking unit for the production of lower boiling constituents including gasoline. The cracking unit is diagrammatically shown at 122 and also includes means for separating the reaction products into desired fractions. The gas oil or other stock is cracked in the presence of powdered catalyst having a size of about 200 to 400 standard mesh or finer. The catalyst may be acid-treated bentonite or synthetic silica-alumina or silica magnesia gel. The temperature during cracking is about 825 to 1000° F. The amount of catalyst to liquid oil by weight is in the ratio of from about 2/1 to 20/1.

Gases are taken overhead through line 124 and bottoms are withdrawn through line 126. A C₄ fraction is withdrawn through line 128 and a C₅ fraction is withdrawn through line 132. The

C₄ fraction contains normal butane and isobutane and butenes. Isobutane from an extraneous source may be added if desired. The C₄ and C₅ fractions are combined and passed through line 134 to an acid alkylation unit 136 where the mixture is treated with sulfuric acid having a concentration of about 98%. The sulfuric acid is introduced into the unit 136 through line 138. The temperature during alkylation is about 40° F. The alkylation is carried out at an internal isobutane/olefin ratio of 250/1.

The C₄ and C₅ alkylate and pentanes are withdrawn through line 142.

The spent acid having a concentration of about 85 to 95% is withdrawn through line 144 and may be used in acid-treating the C₅ to 225° F. cut (or C₆ to 225° F.) and the 225 to 350° F. Or the spent acid may be passed through an acid recovery unit 146 for concentrating the acid to the desired concentration for reuse and recycling to the alkylation unit 136.

The C₆ to 225° F. fraction is withdrawn from unit 122 through line 148 and passed to an acid-treating unit 152 where it is mixed with spent acid introduced through line 154. The spent acid is part of the acid leaving the alkylation unit through line 144. If desired, fresh acid may be introduced into line 154 through line 156.

The acid tank 152 is provided with a stirrer such as shown in Fig. 1 or other stirring means for intimately contacting the light fraction and the sulfuric acid. When using a weaker acid of 85 to 95% concentration, the amount of acid to light fraction may be about 20 to 100 lbs./bbl. of light fraction. The temperature during the

treatment is about 60° F. to 120° F. and the time of contact is about 6 minutes to 60 minutes.

The acid-treated C₆ to 225 fraction is withdrawn through line 158 and is preferably given an alkaline wash (not shown in Fig. 2) and then re-run to remove light and heavy ends. The resulting C₆ to 225° F. fraction has an improved AFD-1C and AFD-3C rating as above pointed out in the description of Fig. 1 and the data included in connection therewith. Spent acid from the acid tank 152 is withdrawn through line 162 and may be recycled to the acid recovery unit 146 through line 144. Part of the spent acid may be withdrawn through line 164.

The heavier fraction (225 to 350° F.) from unit 122 is passed through line 166 to another acid-treating tank 168 where it is mixed with acid introduced through line 172. The acid comprises the spent acid from the alkylation unit 136 and may include fresh acid introduced through line 156. The acid-treating tank 168 may be provided with any desirable stirring means for mix-

ing the heavier fraction and the sulfuric acid. The sulfuric acid has a concentration of about 85 to 95%. About 20 to 100 pounds of acid are used per barrel of heavy fraction. The time of treating is about 6 to 60 minutes and the temperature during the treating is about 60 to 120° F. Spent acid is withdrawn through line 174 and returned to the acid recovery unit 146 for reconcentrating the sulfuric acid.

The acid-treated 225 to 350° F. fraction is withdrawn from the acid-treating unit 168 through line 176 and is preferably given an alkaline wash to remove entrained acid and rerun to remove light and heavy ends. The treated heavier fraction has an increased AFD-1C and AFD-3C IMEP rating as above pointed out in the description of Fig. 1 and the data included therewith. The treated light and heavy fractions may be combined and further processed in one system including a fractionator.

Instead of passing the 225 to 350° F. fraction through the acid-treating unit 168, in some cases it may be used as such without acid-treating. In such case, the heavier fraction is by-passed around the acid-treating unit or tank 168 through line 178 and used as such in the final product.

The final product is formed by combining the acid-treated 225 to 350° F. fraction, the acid-treated C₆ to 225° F. fraction, the alkylate passing through line 142 and an extraneous natural base passing through line 182. The final product in one specific case has the following composition but it is understood that this is given by way of example only as the final product will vary with the quality and nature of the fractions:

Per cent by volume	
C ₆ -225° F.	12.7
225° F.-350° F.	17.0
Pentanes in alkylate	11.7
C ₄ and C ₅ alkylate	40.2
Natural base	18.4

The combined product is withdrawn through line 184 and has an AFD-3C rating of 203 IMEP. The extraneous natural base may have the following composition:

Components	Vol. Per Cent
Aromatics	0-2
Naphthenes	25-38
Paraffins	75-60
Olefins	0

The extraneous natural base has a boiling range of about 100° F. to 200° F. and has an AFD-3C rating of 140-170 IMEP.

Since aviation gasoline is an extremely high grade product, there does exist a supply of readily available natural base stocks, so-called "marginal bases," which are of a high quality compared to normal motor fuel, but are relatively low compared to final 100 octane aviation product. Since this natural base material can be obtained without the installation of any processes or equipment over that available in normal crude processing, the volume of aviation gasoline can be increased by mixing this natural base with higher octane stocks, such as alkylation and/or catalytically cracked naphtha acid treated according to my invention. The losses which accompany acid treating, although high, represent material considerably poorer than the marginal stock, and by removing this poorer material, aviation production is increased. Further, the loss is not a complete one as the polymers recovered from the sul-

furic acid used for treating may be used in motor gasolines.

Optimum treats for individual fractions are such that will eliminate substantially all olefins with a minimum of loss of aromatics. Splitting of the total naphtha assures the minimizing of alkylation by providing unfavorable aromatic to olefin ratios, and one advantage of split treating results from this fact. Since the higher boiling olefins in the heavy fraction are more difficult to remove than the olefins in the light fraction, a more severe acid treat is required to obtain a given quality improvement for the heavy fraction as compared to the light.

My process may be used with low or high sulfur stocks. When using my process for treatment of low sulfur stocks, the improvement in quality is due primarily to the removal of olefins. Naphthas containing sulfur to the extent of about 0.20% are improved to a higher degree because of sulfur removal in addition to the removal of olefins.

While I have specifically set forth fractions of C₆-225° F. and 225 to 350° F., it is to be understood that the split between the fractions may occur anywhere between 175° F. and 275° F., depending on the nature of the catalytically cracked naphtha being treated. Also, more than two cuts may be made and treated, if desired.

While I have shown two forms of apparatus for carrying out my invention and have included specific compositions, conditions, etc., it is to be expressly understood that these are by way of example only and my invention is not to be restricted thereto.

35 I claim:

1. A method of improving the IMEP of catalytically cracked aviation gasolines containing olefins and aromatics which comprises separating a catalytically cracked aviation gasoline into a C₆-225° F. fraction containing a major portion of the olefins and a 225-350° F. fraction containing a major portion of the aromatics, separately treating each fraction with concentrated sulfuric acid having a concentration of about 85 to 98% to remove olefins and then recombining the treated fractions.

2. A method according to claim 1 wherein the sulfuric acid is used in the amount of about 5-60 pounds per barrel of fraction treated, the temperature during treating is 30-120° F. and the time of treating is about 2 to 120 minutes.
